Attorney, Agent, or Firm—Jones & Askew, LLP

CLAIM

The ornamental design for a container caddy, as shown and described.

DESCRIPTION

FIG. 1 is a perspective view of our new container caddy; FIG. 2 is a front elevation view thereof; FIG. 3 is a right side elevation view thereof; FIG. 4 is a top plan view thereof; FIG. 5 is a left side elevation view thereof; FIG. 6 is a bottom plan view thereof; and, FIG. 7 is a back elevation view thereof.

The broken lines showing the recessed area, the contoured bottles, and the emblem circle are for illustrative purposes only and do not form part of the claimed design.
